Primary Examiner — Keli L Hill*Assistant Examiner* — Sara S Sahneh(74) *Attorney, Agent, or Firm* — IPro, PLLC(57) **CLAIM**

The ornamental design for a hand-held code reader, as shown and described.

DESCRIPTIONFIG. 1 is a top, front and right side perspective view of a hand-held code reader showing our new design;
FIG. 2 is a bottom, rear and right side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of portion 9 in FIG. 1.

The broken lines shown are included for the purpose of illustrating portions of the hand-held code reader that form no part of the claim. The dash dot dash lines in FIGS. 1 and 9 are for the purpose of depicting the cut line of the enlarged view and form no part of the claimed design.
